UNITED STATES PATENT OFFICE.

EDWARD G. HODGES, OF MARSHALLTOWN, IOWA.

AUTOMATIC AIR-SUPPLY DEVICE AND COMBINATION-GOVERNOR THEREFOR.

1,276,762.

Specification of Letters Patent. Patented Aug. 27, 1918.

Application filed February 4, 1918. Serial No. 215,414.

To all whom it may concern:

Be it known that I, EDWARD G. HODGES, a citizen of the United States, and resident of Marshalltown, in the county of Marshall and

5 State of Iowa, have invented a certain new and useful Automatic Air-Supply Device and Combination-Governor Therefor, of which the following is a specification.

My invention relates to devices for supplying air to the mixture being fed to the cylinder of an explosive engine after the mixture has left the carburetor.

10 The object of my invention is to provide means for supplying air to the fuel mixture, 15 as just mentioned, which means includes a supply pipe having a valve therein, and mechanism for automatically regulating the position of said valve.

Still a further object is to provide such a 20 device having the elements hereinbefore set forth, and so constructed and arranged and connected with the other parts of the engine and carbureting means, that the passage of air from said pipe is, to a certain extent, controlled by the position of the throttle valve 25 of the carbureting device.

By the construction set forth, the air supplied to the mixture through said pipe is determined by the position of the valve in 30 said pipe, which is in turn regulated according to the engine speed and also by the position of the throttle valve in the carburetor.

Still a further object is to provide a device of the kind mentioned in which the 35 valve in said pipe is connected with certain devices whereby its position is regulated by the flow of water through the circulating system of the engine and also by the blast of air from the fan and from the forward 40 movement of the car on which the engine is mounted.

With these and other objects in view my invention consists in the construction, arrangement and combination of the various 45 parts of the device, whereby the objects contemplated are attained, as hereinafter more fully set forth, pointed out in my claims and illustrated in the accompanying drawings, in which:

50 Figure 1 shows a side elevation of an engine equipped with an automatic air supply device and combination governor there-

for embodying my invention, the parts being shown in section; and

Fig. 2 shows a vertical, sectional view 55 taken on the line 2—2 of Fig. 1.

In the drawings herewith I have used the reference numeral 10 to indicate generally an internal combustion engine of the water cooled type having the passage 11 60 leading from the engine water jacket to a suitable radiator not shown. The engine is of the type used on a motor vehicle and has the cooling fan 12. There is provided adjacent to the engine 10 a carburetor 13 which 65 communicates by means of the tube 14 with the intake manifold of the engine. In the passage 14 is the ordinary butterfly throttle valve 16.

Communicating with the passage 14 between the throttle valve 16 and the fuel nozzle 17 of the carburetor, is a pipe 18 in which is a flap check valve 19.

The pipe 18 communicates with a pipe 20 which, at a certain point in its length, has 75 a valve casing 21. The pipe 20 may be open to the air or may, for the purpose of raising the temperature of the air passing therethrough and supplying mixture, be extended to any suitable point. 80

Communicating with the passage 14 at a point between the throttle valve 16 and the engine is a tube or passage 22 which also communicates with the pipe 20, as shown in Fig. 1. 85

In the casing 21 is a butterfly valve 23 having a stem 24 extending through the wall of the casing. Secured to the stem 24 in any suitable manner is a transversely arranged rod 25 on which is mounted an air vane 90 26 arranged to stand at right angles to the path of air driven rearwardly by the fan 12 or passing rearwardly through the radiator.

Pivoted to the rod 25 on the side of the stem 24 or opposite the vane 26 is a link 27 95 which extends forwardly in the machine, as shown in Fig. 1.

The pipe or passage 11 is provided with a valve casing 28 in which is mounted a flap-valve 29 adapted to coact with a seat 30 in 100 said casing.

The valve 29 has a stem 31 extending through the wall of the casing 28. Fixed between its ends to the stem 31 is a lever 32,

- the lower end of which is pivoted to the forward end of the link 27. A portion of the lever 32 extends upwardly above the stem 31 and is secured to a suitable spring 33, which 5 may be secured to a clamp 34 or any other fixed member. Any suitable means for yieldingly tending to hold the valves 29 and 23 in closed position may be employed in place of the spring 33.
- 10 In the practical use and operation of my improved automatic air supply device and combination governor therefor, it will be obvious that when the engine is being started, there will be comparatively little draft 15 of air passing rearwardly past the vane 26, and comparatively little circulation of water through the passage 11, so that the valve 23 will be practically closed during the starting of the engine, the mixture going from the 20 carbureter in the ordinary way to the engine cylinders.
- Whatever leakage may occur past the valve 23 during starting may be compensated for by regulating the carbureter in the 25 ordinary way for securing the proper mixture for starting.
- As the engine acquires greater speed the blast of air against the vane 26 and the movement of water through the passage 11, where- 30 by the valve 29 is moved, will tend to open the valve 23 for allowing a greater amount of air through the valve 23 and thence through the pipes 18 and 22 to the mixture.
- I have found by experiments that without 35 my device, especially while the engine is running with a light load or is idling, where the carbureter throttle is open sufficiently to supply enough mixture to the cylinders to secure a proper explosion, the mixture is 40 richer than necessary. On the other hand, where the throttle is moved toward closed position for reducing the richness of the mixture, there is not sufficient fuel and air supply to secure proper compression.
- 45 Where my device is used, it will be seen that when the engine is idling or running rapidly with a light load, as for instance an engine is running at high speed on level ground or running down grade, there is sup- 50 plied to the mixture passing into the cylinders air from the air supply pipe 20, whereby the mixture is thinned for effecting a substantial saving of fuel, while at the same time furnishing to the cylinders a constant 55 volume of mixture for securing compression. Thus when little or no power is needed to drive the engine, after I get the car up to the desired speed, I close or nearly close the throttle valve and allow the engine to take 60 in air through the air pipe 20. Where a little more power is necessary to keep up the required speed, the throttle is opened slightly allowing more of the mixture in the carbureter to come up and mix with the air com-

ing from the air supply pipe 20, and on account of the engine receiving the full volume on each charge I secure proper compression and a clean explosion sufficient to maintain the required speed. When the engine is subjected to greater load, as in going up grade, 70 or under any condition where greater power is needed, the throttle valve is opened for permitting the engine to take more of its charge through the carbureter. It will be obvious that the more the throttle valve is 75 opened the less air will be drawn through the pipe 20 on account of the resistance through said pipe, on account of its smaller size, and the mixture supplied to the engine will be nearer the normal mixture supplied 80 from the carbureter without the auxiliary air supply and of the proper richness for a heavy load.

The check valve 19 is provided in order to prevent the passage of a rich mixture from 85 the carbureter through the pipe 18 and the pipe 22, when the engine is running with a light load or is idling and the throttle valve is closed or almost closed. When the throttle valve is open, air will be drawn through 90 the pipe 18 as well as through the carbureter and the pipe 22.

Good results will be obtained by a device of the kind hereinbefore described where either of the governing devices is employed. 95 I have found, however, that by using both the air blast governor and the water flow governor there is secured an evener and steadier control of the valve 23, than where one of the governors only is used.

When the engine is being started and until it has reached a certain speed I have found that the blast of air on the vane, particularly if the car is not moving, does not open the valve 23 as much or as evenly as might be 105 desired, and have found that the gradual opening of the valve 23 is better secured by the use of the water flow governor combined with the air governor. After the engine has acquired speed and particularly after the 110 car is running at a high speed, I have found that the air blast, which affects the vane 26, is created not only by the fan but also by the speed of the car, which causes a blast of air through the radiator against said vane, 115 for combining with the water flow governor in controlling the valve 23.

Among the further advantages attained by the use of a device of this kind, may be mentioned the fact that it reduces the deposit of carbon in the engine on account of not allowing the engine to load up with unnecessary rich fuel while idling.

Where a device of this kind is not used it frequently happens that when the engine 125 is idling it becomes loaded up with fuel and lubricating oil, and then when it is necessary to secure quick action from the engine in

climbing a hill or the like it is necessary to clean out the surplus fuel. Where a device of the kind herein described is employed, there is no loading up with fuel and hence

- 5 no scavenging of the engine is necessary for getting such quick action, and proper action of the engine can be secured more quickly after the engine has been idling.

Where a device of this kind is not used, 10 it will sometimes happen that when the engine is idling or running at high speed with a light load, the throttle is closed to reduce the speed or avoid the increase of speed, and as result the volume of mixture supplied is 15 not sufficient and the greater vacuum in the cylinders causes lubricating oil to be drawn up from the crank case into the cylinders in an amount greater than is necessary, thereby resulting in the formation and deposit of carbon in the cylinders. This objectionable feature is also obviated by supplying a full volume of mixture in the manner hereinbefore described.

It will be seen that with the use of my 25 device I effect a saving both of fuel and of lubricating oil.

An incidental advantage which occurs from the use of my combination governor arises from the fact that the valve 29 and spring 33 tend to prevent the circulation of 30 water through the circulating system of the engine until after the engine has become heated.

It will be seen that as the water becomes 35 hot the pressure of the water on the valve 29, tending to open said valve, increases; and when the water becomes hot enough the valve 29 is opened somewhat. When the blast of air reaches a certain strength the 40 valve 26 will be operated for contributing to the opening of the valve 23 and at the same time the action of the air blast on the vane 26 assists in opening the valve 29, thereby affording proper circulation of 45 water through the circulating system and preventing the water from becoming too hot.

The tension on the spring 23 should be 50 adjusted in such a way that both the valve 23 and the valve 29 are fully opened after the car has acquired its usual high speed.

Where my device is used on an engine 55 having a carburetor provided with a suitable means for supplying air to the fuel mixture passage between the throttle valve and the fuel nozzle in the carburetor or wherever the pipe 22 is sufficient to supply auxiliary air the lower pipe 18 and the check valve 19 may be dispensed with.

60 The combination governor herein shown is intended for engines that have a water circulating pump. The same arrangement can be applied to engines that depend only on the thermostat siphon system. The de-

vice is intended to be used on all motor 65 driven vehicles including aeroplanes, motor boats and so forth, having explosive engines with a manually controlled throttle.

While I have shown and described a butterfly valve for controlling the passage of 70 air through the auxiliary air supply device, it is my intention to cover any form of valve which would be adapted for accomplishing the purpose.

Changes may be made in the construction 75 and arrangement of the parts of my device, and the parts may be made of any material suitable for the purpose without departing from the essential features and purposes of my invention, and it is my intention to 80 cover by my claims any modified forms of structure or use of mechanical equivalents which may be reasonably included within their scope.

I claim as my invention:

1. An automatic air supply device and combination governor therefor, comprising an air supply pipe, means for controlling the passage of air therethrough, an air vane operatively connected with said means, 90 and means designed to be actuated by the flow of water through the circulating system of an engine operatively connected with said first means.

2. In a device of the class described, the 95 combination of an internal combustion engine of the water cooled type, with an air supply device and combination governor therefor, including a pipe, a valve in said pipe, a vane operatively connected with said valve adapted to be acted on by air blasts, and means actuated by the passage of water through the circulating system of the engine 100 operatively connected with said valve.

3. In a device of the class described, the 1 combination of an internal combustion engine of the water cooled type and having a carburetor with a throttle valve, with an automatic air supply device and combination governor therefor, comprising an air 110 supply pipe, a pipe leading therefrom to the fuel mixture passage of the engine above and below said throttle valve, a check valve in the pipe below the throttle valve, a valve in said first air supply pipe, and means for 115 controlling the position of said last named valve according to the movement of air and according to the movement of water through the circulating system of said engine.

4. In a device of the class described, the 120 combination of an internal combustion engine of the water cooled type and having a carburetor with a throttle valve, with an automatic air supply device and combination governor therefor, comprising an air supply 125 pipe, a pipe leading therefrom to the fuel mixture passage of the engine above and below said throttle valve, a check valve in

the pipe below the throttle valve, a valve in said first air supply pipe, having a stem, a vane operatively connected with said stem, a valve arranged to be operated by the movement of water passing through the circulating system of the engine, and means for operatively connecting said last named valve with said stem.

5. In a device of the class described, the combination of an internal combustion engine of the water cooled type and having a carbureter with a throttle valve, with an automatic air supply device and combination governor therefor comprising an air supply pipe, a pipe leading therefrom to the fuel mixture passage of the engine above and below said throttle valve, a check valve in the pipe below the throttle valve, a valve in said first air supply pipe, having a stem, a vane operatively connected with said stem, a valve arranged to be operated by the movement of water passing through the circulat-

ing system of the engine, means for operatively connecting said last named valve with said stem, and yielding means for normally tending to hold the valve in said air supply pipe in closed position. 25

6. In a device of the class described, the combination of a water cooled explosive engine, with an auxiliary air supply pipe, a valve therein, a valve arranged in the circulating system of the engine, and means for operatively connecting said valves. 30

7. An automatic air supply device and combination governor therefor comprising an air supply pipe, a valve therein having a stem, a vane operatively connected with said stem, a second valve designed to be placed in the circulating system of a motor cooled explosive engine, and means for operatively connecting said last named valve with said stem. 35 40

Des Moines, Iowa, December 27, 1917.
EDWARD G. HODGES.
